UNITED STATES PATENT OFFICE.

GEORGE A. LEIGHTON, OF ROSLINDALE, MASSACHUSETTS, ASSIGNOR TO AMERICAN CAN COMPANY, OF NEW YORK, N. Y., A CORPORATION OF NEW JERSEY.

FRICITION-TOP CAN.

Application filed April 19, 1920. Serial No. 374,795.

To all whom it may concern:

Be it known that I, GEORGE A. LEIGHTON, a citizen of the United States, residing in Roslindale, in the county of Suffolk and 5 State of Massachusetts, have invented a new and useful Improvement in Friction-Top Cans, of which the following is a specification.

This invention relates in general to friction top cans and has for its object broadly 10 the provision of a friction top can, the friction top or plug of which may be readily pried off or removed by the use of a coin or any handy tool or implement.

15 An important object of the invention is the provision of a can of this character, the top and body of which will be so constructed that the cover may be pressed down tightly to closed position without 20 rendering difficult the insertion or manipulation of the coin or tool and without danger of inaccurate engagement of the inter-engaging friction walls of the cover and body.

25 Another important object of the invention is the provision of a can of the character described and having the advantages mentioned, which will provide a full face smooth surface of the top when the latter 30 is being pushed into closed position.

Another important object of the invention is the provision of a top for such a can, which can be easily and cheaply manufactured and which may be safely handled 35 without danger and which can be used with any body having an opening of appropriate dimensions to receive it.

Numerous other objects and advantages 40 of the invention will be apparent as it is better understood from the following description, which taken in connection with the accompanying drawing discloses a preferred embodiment thereof.

Referring to the drawing.

45 Figure 1 is a perspective view of a can embodying my present invention;

Fig. 2 is a transverse sectional view taken on the central axis of the can shown in Fig. 1; and

50 Fig. 3 is a partial side elevation thereof.

For the purpose of illustrating my present invention I have shown on the drawing a can body formed of a cylindrical wall 11, closed at its bottom by a suitable closure 55 12 and having an inwardly extending an-

nulus 13 at the top seamed at 14 to the upper edge of the wall 11. This annulus is bent up at 15 to a horizontal or flat portion 16 and therebeyond to provide a friction wall forming flange 17 extending inwardly of the can body.

The top or friction plug consists of a central circular part 18 surrounded by a substantially cylindrical portion 19 which provides a friction wall for engagement 60 with the friction wall 17 of the annulus. A shoulder 21 is provided above the friction wall 19 and extends outwardly continuously around the top for engagement with the horizontal part 16 of the can body. The 65 top is provided with an outwardly extending pry-off flange 22 spaced above the shoulder 21 by a vertical cylindrical portion 23, said pry-off flange being bent back upon itself as indicated at 24 in Fig. 2. 70

The interengaging parts of the cover or top and the body, i. e., the shoulder 21 of the top and the flat portion 16 of the body, space the flange 24 above the part 16 of the body evenly and at the required distance 80 and insure accurate engagement between the interengaging friction walls.

It will be manifest that the can described can be cheaply and easily manufactured and that the tops, being strong, are not 85 easily damaged in shipment and handling.

It is thought that the invention and many of its attendant advantages will be understood from the foregoing without further description, and it will be apparent 90 that various changes may be made in the form, construction and arrangement of the parts described without departing from the spirit and scope of the invention or sacrificing any of its material advantages, the 95 form hereinbefore described being merely a preferred embodiment thereof.

I claim:

A friction-top can, comprising a body 100 provided at its top with an inwardly extending annulus the outer part of which is united with the upper part of the body, the inner part of said annulus being bent up and formed with an opening and with a friction seat wall surrounding said opening, and a cover formed with a smaller and inner cylindrical part having a friction seat wall adapted to fit the said seat wall of the annulus and form a tight closure therewith, and formed above said smaller 110

cylindrical part with a larger and outer cylindrical part, between which cylindrical parts is a shoulder adapted to engage on top of said annulus when the can is fully closed and thereby limit the insertion of the friction seat wall of the cover within the friction seat wall of the annulus, the cover having an outwardly extending flange which is spaced above the bent-up part of said annulus by means of said shoulder, the said outer cylindrical part being of less diameter than said bent-up part and said flange. 10

GEORGE A. LEIGHTON.
